COSMETIC HOLDER

Hyman R. Segal, New York, N. Y.

Application August 6, 1935, Serial No. 34,948

11 Claims. (Cl. 206—53)

This invention relates to new and useful improvements in cosmetic holders and more particularly to holders for lipsticks, eye-brow pencils and the like.

5 An object of the invention is to provide a cosmetic holder which will be simple in construction, convenient and reliable in operation and particularly advantageous from a manufacturing standpoint.

10 Another object is to provide a holder for cosmetic sticks having spaced openings for the sticks, and which completely encloses and protects the cosmetic when the latter is not in use.

Another object is to provide a cosmetic holder 15 having opposite openings for cosmetic sticks, and a simple and positively actuated means which may be easily operated to project a cosmetic stick from either opening for use and retract it into concealed position within the holder after use.

20 Another object is to provide in a cosmetic holder continuous means for moving the cosmetic with respect to the holder casing and for controlling the casing openings.

25 Another object is to provide a container for a plurality of cosmetic sticks, which may be of different kinds, the container having a plurality of openings for the cosmetic sticks and closure means for the openings arranged to be actuated to move the sticks selectively through the openings.

30 In the field of cosmetics there has been observed an increasing demand for cosmetics in stick form. Satisfaction of this demand has been impeded somewhat due to the lack heretofore of containers or holders for the sticks which would be convenient for operation with one hand and at the same time compact so as to readily fit into small compartments in ladies' handbags and garments. Some attempts to meet requirements 35 have been made and containers have been constructed which not only completely enclose the cosmetic when the latter is not in use but also include slide means within the container communicating with an external lug for actuation by the user's finger to automatically open the container as the cosmetic stick is advanced to extend from the container for use.

40 Heretofore, such devices have employed as the slide means a section of metal ribbon or tape having its edges bearing in flanges formed within the casing. A cosmetic stick is fast on one end, and adjacent the other end is the actuating lug movable along a slot cut in the casing of the 45 container. One half of the action of the slide is

a pushing operation, however, and experience has shown that the metal ribbon frequently buckles in the bearing flanges because of the friction involved in advancing the cosmetic stick along the container.

5 Most recently has there developed the custom of carrying on the person a number of different cosmetic sticks, not only the eye-brow pencil in addition to the conventional lip-stick, but at least one extra lip-stick of a contrasting shade. 10 The extra lip-stick accessory is occasioned by the realization that different kinds of light produce varying effects upon cosmetic shades, it being considered increasingly important that there be readily available, for instance, a lip-stick shade 15 suitable for day-time or natural day-light and the other shade appropriate for evening or for artificial light.

The present invention contemplates the provision of a casing of special design in a container 20 for a plurality of cosmetic sticks, having opposite openings through which the sticks may be extended. Furthermore, the present device employs an endless tape as a carrier for the cosmetic sticks, which is adapted to be actuated to 25 advance or retract the sticks selectively through the casing openings and to insure the complete closing of the openings when not in use.

The invention will be more readily understood by reference to the following detailed description 30 taken in connection with the accompanying drawing forming a part thereof, in which:

Fig. 1 is a perspective view of the three longitudinal sections of a preferred type of casing for a cosmetic stick container having two open ends; 35

Fig. 2 is a perspective view showing a modified construction of the side plates shown in Fig. 1;

Fig. 3 is a perspective view of a modified type of casing composed of two longitudinal sections; 40

Fig. 4 is a perspective view of a modified construction of side plate for use with the forms shown in Figs. 1 or 3;

Fig. 5 is a perspective view of the endless cosmetic stick carrier tape, adapted for use with the 45 casings referred to above;

Fig. 6 is a perspective view of a modified form of endless carrier tape;

Fig. 7 is a perspective view of a modified form of endless carrier tape; 50

Fig. 8 is a perspective view of a modified form of carrier tape;

Fig. 9 is a view in elevation on an enlarged scale showing a clip for engaging the cosmetic stick; 55

Fig. 10 is a view in section on a corresponding scale showing a box for receiving the clip shown in Fig. 9;

Fig. 11 is a sectional view showing the double-opening cosmetic stick container assembled in closed condition;

Fig. 12 is a view corresponding to Fig. 11 showing one end open and in use;

Fig. 13 is a view corresponding to Fig. 12 showing the opposite end open and in use, this form modified to illustrate the use of two opposite finger lugs;

Fig. 14 is a sectional view on the line 2—2 of Fig. 11, enlarged to correspond in scale with Figs. 9 and 10, illustrating in detail the assembly, channels for the endless carrier and the cosmetic box way;

Fig. 15 is a sectional view corresponding to Fig. 14, but illustrating in detail the assembly with the integral side wall of Fig. 3;

Fig. 16 is a sectional view corresponding to Figs. 14 and 15, but illustrating the assembly with grooved side walls shown in Fig. 2;

Fig. 17 is a sectional view corresponding to Fig. 11, but showing the container with the single opening carrier tape of Fig. 7, and a single cosmetic stick; and

Fig. 18 is a view corresponding to Fig. 16, but showing the container with the modified carrier tape of Fig. 8.

Referring to the drawing, in which similar parts are indicated by identical reference numerals, the preferred embodiment of my invention, as shown in Figs. 1, 5, 9, 10, 11, 12 and 14 of the drawing, includes an outer casing 1 comprising an integral body member 2 preferably having straight parallel front and back portions 3 and 4 connected by rounded end portions 6 and 7. The body member 2 is recessed at opposite edges 8—8 to receive side plates 9 and 11 which have straight parallel side edges 12—12 and rounded end edges 13—13 to fit the front and back portions 3 and 4 and the end portions 6 and 7, respectively, of the body member.

On the inner surface and spaced from the periphery thereof, the side plates 9 and 11 each have a smooth, continuous shoulder 14. As shown in Figs. 11 and 14, the shoulders 14—14 are spaced inwardly from the inner surface of the body member 2 a sufficient distance to accommodate for easy traverse therebetween an endless carrier belt 16 for a cosmetic stick box 17.

When the side plates 9 and 11 are forced, glued or otherwise suitably secured in the recesses 8—8, the side openings of the body member 2 are entirely closed. The described three-piece casing may be made, for example, of die casting or moulded plastics; the latter method, especially, enabling the achieving of very attractive effects by means of contrasting colors in the materials of the body member and the side plates. In either case, the construction promotes economical manufacture, since the body member may be produced in larger quantities in a particular finish, and the side plates made in smaller quantities of various finishes.

The invention essentially includes a plurality of openings in the container casing through which may be caused to project cosmetic sticks, to the end that the container cosmetic supply might afford the requisite variety, such as lip-stick and eye-brow pencil, or two lip-sticks of different shades. The drawing illustrates such openings provided in the present elongated or cartridge type of container, although such con-

struction may be readily embodied in casings of different shape, if desired. In the body member 2, midway of the edges 8—8, the rounded end portions 6 and 7 are pierced with aligned rectangular apertures 18 and 19, respectively. The front portion 3 has an elongated opening or slot 21.

The belt or carrier tape 16, as shown in Fig. 5, is a length of ribbon sufficiently wide to extend across the interior of the casing 1, the lateral edges of the tape lying upon the opposite side plate shoulders 14—14 which form a loop-shaped guideway therefore along the entire extent of the under-surface of the body member 2. Preferably, the tape 16 is thin flexible metal similar to the type used in reeled measuring tapes, it being desirable that it flex or bend readily in moving on the rounded ends of the casing but yet be stiff sufficiently to withstand the pushing action tending to cause the tape to ride from or crumple in the guideways of the container. In the construction shown, wherein there is chiefly employed a continuous or endless tape, it is possible to use a much lighter weight of ribbon than heretofore, since pushing pressure applied at any point tending to move the ribbon longitudinally is distributed in pulling force as well, thus all parts of the ribbon share the strain and rumpling and dislocation of the tape is eliminated.

Preferably, the carrier tape is composed of a section of material equal to the circumference of the side plate shoulders 14. Adjacent each end the section is formed with rectangular openings 22 and 23, sufficient material being left in the form of bearing strips 24 and 26 for continuous support on the shoulders 14. Intermediate the ends the tape is provided with a centered aperture 27. The tape is looped by bringing the ends together and butt-welding them as at 28, a centered aperture 29 being formed at the weld. A rivet 30 extends through the aperture 29 to fasten the cosmetic stick box 17 upon the inner surface of the carrier tape 16.

Cosmetic sticks 32 and 33, which may represent lip-sticks of light and dark shades respectively, are secured together, their bases abutting, by means of a light wire clip 34. The clip 34 may be U-shaped, with the web apertured to receive the stick, and the wings 36—36 having inwardly-pointing prongs 37 which are embedded in the base of each stick. The retaining box 17 is an open-ended rectangular casing corresponding with the internal dimensions of the container between the opposite courses of the tape 16, and has inwardly extending upper and lower flanges 38 and 39 which engage the clip 34 to fix the cosmetic sticks against movement from the box. Assembled within the container as shown in Fig. 11, the cosmetic sticks are centered longitudinally of the container, the carrier tape 16 is fitted in the guideways formed by the shoulders 14—14 and the rectangular openings 22 and 23 in the tape lie along the back portion 4 of the body member. The centered aperture 27 of the tape is fitted with any suitable operating element such as a finger lug 41, which is headed over the front portion 3 of the body member and has a shank 42 secured in the aperture 27.

By reference to Figs. 11, 12 and 13, the operation of the invention will be apparent. Normally, the cosmetic sticks are centered within the container as shown in Fig. 11, the end apertures 18 and 19 in the outer casing being tightly closed by the tape 16 and the finger lug 41 being positioned midway of the ends of the elongated slot 21.

21 on the front of the container. Assuming that it is desired to use the lighter lip-stick 32, the container is held in the hand and the thumb applied to press the lug 41 upwardly. Pushing of the lug 41 is translated into a combined pushing and pulling force which slides the tape evenly along the shoulders 14—14 to the position shown in Fig. 12, wherein it will be noted that the rectangular opening 22 coincides with the casing aperture 19 and the box 17 engages the end of the container casing to extend the lip-stick 32 to its fullest extent. After use, the lip-stick 32 is drawn back into the container and the aperture 19 tightly closed by sliding the lug 41 back 15 to the longitudinal center of the slot 21, the tape sliding along the shoulders 14 and the portion having the rectangular opening 22 returning to normal position at the back portion 4. When it is desired to use the darker lip-stick 33, the finger lug 41 is pressed downwardly, causing the tape to slide to present the rectangular opening 23 to coincide with the casing opening 18, and advancing the lip-stick 33 therethrough to position for use. After use the container may be closed by 20 moving the lug 41 upwardly to the center of the slot 21, the tape sliding around to return the lip-stick box to the center of the container and moving across the end of the container to close the aperture 18.

30 The above-described preferred construction has been found to be highly economical to manufacture because of its simplicity, and has proven satisfactory in point of reliability and convenience in use. However, the invention contemplates a number of modifications which, under certain conditions, will be found to contribute to the advantages of the invention.

The modified form of casing shown in Fig. 3 is very similar to the casing illustrated in Fig. 1, 40 but differs therefrom in that a side wall 44' is cast integral with a main body member 43. The casing assembly is completed by the addition of a side plate 44, which is received in suitable recesses 46—46 in the edge of the main body member 43. The side plates or walls 42 and 44 are provided with internal shoulders 47, corresponding to the shoulders 14 of the preferred embodiment, for accommodating the endless carrier tape (not shown). Casting a side wall integral with 45 the body member enables a marked economy in manufacturing cost; however, a qualifying factor is the consideration that the integral construction limits the variety of ornamental effects obtainable otherwise. In other respects the modification of Fig. 3 is identical with the preferred form, and fitted to receive the described operating elements for action as outlined above.

Fig. 4 illustrates a modified side wall or plate, suitable for use with the casing constructions described above. It differs from the prior forms in that the side plate 51 carries on its exterior a mirror 52. The plate 51 is formed with a groove 53 which receives the mirror, and any suitable known means may be employed to retain the mirror in place therein. The mirrored construction is particularly convenient to the user, inasmuch as the lip-stick is frequently applied without the benefit of a convenient hand mirror, and the small glass on the outside of the container 65 enables ample inspection when the cosmetic is being properly distributed after application.

In lieu of the preferred butt-weld method of joining the ends of the carrier tape, Fig. 6 depicts an alternative method including the forming of 70 a tongue 54 on one end of the tape and bending

it off-set to lap the other end, and joining the ends by a lap-weld as at 56. The tongue 54 is apertured at 57 for riveting thereto a cosmetic box 58. Although the modified construction is perhaps stronger than the preferred butt-weld; some additional changes may be necessary when it is employed. For example, the extra thickness on the inner surface of the carrier ribbon caused by the provision of the tongue 54 requires that the box 58 be smaller than the box 17 in order to fit the standard casing. To provide suitable bearing for the box 58, the casing may be formed as shown in Figs. 2 and 16, wherein it will be noted that side plates 59 thereof are relatively thick as compared to the preferred form, and have, on their inner surface, a longitudinal channel 61 in which the box 58 may be moved upon operation of the carrier ribbon. Side plates of the modified character may be employed whenever the cosmetic box used is relatively smaller than the box 17, and the thickness of the side plates 59 and the depth of the channel 61 will be adequate to center the cosmetic box in the path extending between the end openings of the casing.

Fig. 13 illustrates a construction identical with the preferred form, except that an elongated guide slot 62 extends longitudinally in the back portion of the container casing. The shank of a supplementary finger lug 63, similar to the lug 41 for operating the endless tape, extends through the slot 62 and is secured in a centered aperture 64 formed at a butt-weld 66. Such provision of finger-operated elements on both front and back of the container is a convenience to the user in that either or both elements may be pressed to open or close the container, and renders it unnecessary to position a single face of the container to the user's thumb.

An important advantage of the constructions described above, in which is significant the provision of spaced openings for cosmetic sticks in the casing of the container, is that the casing is capable of use in combination with a variety of styles of cosmetic supply and carrier tapes therefor. For example, there is a recognized demand for a container suitable for high-grade advertising purposes. Figs. 7 and 17 show a modified construction practicable for such a use. The endless tape 68 is identical with the preferred tape 16 previously described except that it has but one rectangular aperture 69 therein. The single aperture 69 is sufficient when but one cosmetic stick 71 is fastened to the tape 68, as by a rivet 72. When assembled as shown in Fig. 17, both casing openings 74 and 76 are closed by the tape 68. When the operating lug 77 is moved downwardly, the tape is slid around to present the aperture 69 to the upper casing opening 74 and simultaneously cause the stick 71 to project therethrough for use. The stick 71 may be retracted and the opening 74 closed by pressing the lug 77 upwardly and restoring the tape to the position shown in Fig. 17. During this cycle of operation the lower casing opening 76 remains closed by the continuous web of the tape 68 sliding thereby. When suitable advertising or other type of legend is printed or engraved on the tape as at 78, Fig. 7, actuation of the lug 77 will cause said legend to move across the lower opening 76, the latter acting as a scanning window for the legend.

Figs. 8 and 18 illustrate a simplified form of double-opening, single-stick container wherein the cosmetic box 81 having therein a single cosmetic stick 82 is provided with opposite casing end openings 83 and 84. A measurable saving in

manufacturing cost is achieved by substituting for the endless tapes of the above-described forms a non-continuous carrier tape 86. A centered aperture 87 is formed on one end of the tape 86 to the inner surface of which the cosmetic box 81 is secured, as by a rivet 88 engaged in the aperture 87. The tape 86 travels between continuous shoulders 89 on the side plates and the casing body member 91, which latter may be identical with the preferred body member 2, and has a centered aperture 92 to secure an operating lug 93 slidable in the casing slot 94. The aperture 92 is adjacent the free end 96 of the carrier tape 86 but spaced therefrom sufficiently to allow the end 96 to close the upper casing opening 83 when the cosmetic is not in use. Referring to Fig. 18, when the operating lug 93 is pushed to the lower limit of the slot 94, the cosmetic box 81 is pushed to the upper opening 83, the tape end 96 sliding therefrom to permit the cosmetic stick 82 to be extended therethrough. When the finger lug 93 is restored to the upper end of the slot 94, the cosmetic stick is retracted within the holder and the opening 83 is closed by the tape end 96 sliding thereacross. During the described cycle of operation, it will be noted that the lower casing opening 84 is always closed by the tape 86. If desired, any suitable indicia or legend 97 may be placed on the tape intermediate its ends for display through the opening 84, or the tape may be left blank. In the construction here described, the lug 93 applies a pushing force on the tape to extend the cosmetic through the opening 83 in the initial operation as well as in the final operation when the free end 96 is advanced to close the opening 83.

Although the foregoing description refers to the double end cosmetic stick as comprising different shades or materials, the double end stick may be of one shade, in which event the double end case has the advantage of sparing the user the usual inconvenience of getting a certain end toward the top of the hand. Provision of the double-opening casing permits ejecting the one-shade, double-end lip stick from either end of the casing.

Mounting the cosmetic sticks by means of clips in boxes to be attached to the carrier tape is particularly advantageous from the manufacturing standpoint because it permits assembling small lots of various makes or different shades of cosmetics after complete large lots of the cases are made.

In assembling containers of the types shown principally in Figs. 1 and 3, one side wall may be left off while the push button is attached to the tape and other assembly work within the case is done in view of the mechanic. Assembly within the case being completed, the container may be completed by merely fitting the second side plate in place to fully close the container.

The exterior of the container may be provided with any suitable scheme of contrasting colors or indicia whereby the user may readily determine, without opening the container, at which end a cosmetic stick of a desired characteristic is located. For instance, if the sticks 32 and 33 are lip-sticks of light and dark shades, respectively, then the opposite ends of the casing may be marked "L" and "D" to correspond therewith.

It should be understood that the disclosed arrangements are susceptible of various modifications without departing from the spirit of the invention, and the invention should not, there-

fore, be limited except by the scope of the appended claims.

What I claim is:

1. In a container for cosmetic sticks, a casing having a pair of opposed stick openings therein, guide means within the casing extending between said stick openings, a pair of opposed cosmetic sticks extending respectively toward said openings, an endless tape in loop formation on the guide means for carrying the sticks and provided with openings to register with the casing openings to permit projection therethrough of the sticks, said sticks being disposed interior of said looped tape, and means exterior of said looped tape for moving the tape between the casing openings to advance and retract the sticks with respect thereto.

2. In a container for cosmetic sticks, a casing having a pair of opposed stick openings therein, guide means within the casing extending between said stick openings, a supply of cosmetic in stick form extending toward said openings, an endless tape in loop formation on the guide means for carrying the cosmetic stick normally closing both openings, and provided with openings to register with the casing openings to permit projection therethrough of the sticks and means for moving the tape on said guide means to open one of the openings and advance one of the sticks therethrough.

3. A combined closure means and cosmetic stick carrier for cosmetic stick containers comprising an endless loop formed of an elongated section with ends butt-welded, the carrier being characterized by the provision therein of an aperture for the accommodation of a cosmetic stick.

4. A container for cosmetics in stick form including in combination, a casing having an opening at each end, a member for retaining a cosmetic supply and movable in said casing between said casing openings, a flexible member in said casing operatively connected to said retaining member for movement of the cosmetic toward either of said openings to project therethrough and for movement of the cosmetic inwardly of the casing to withdraw the same from either of said openings, said flexible member closing said openings when the cosmetic is moved inwardly therefrom and being provided with openings to register with the casing openings to permit projection therethrough of the cosmetic supply.

5. A container for cosmetics including a casing having an opening at each end, side walls for the casing, continuous shoulders on the side walls defining a guide-way between the openings, a cosmetic supply, and continuous flexible means positioned on said shoulders for movement of the cosmetic supply toward either of said openings to project therethrough and for movement of the cosmetic supply inwardly of the case to withdraw the same from either of said openings, said continuous flexible means closing said openings when the cosmetic is moved inwardly therefrom and being provided with openings to register with said casing openings to permit projection therethrough of the cosmetic supply.

6. In a container of the class described, a casing having openings at opposite ends, a cosmetic supply in said casing, a flexible member in said casing secured to said cosmetic supply and movable between the openings, said flexible member normally closing said casing openings and being provided with openings to register with said casing openings to permit extension therethrough of the cosmetic supply, and means for selectively

moving the flexible member to extend the cosmetic supply through said openings.

7. A container for a cosmetic supply including a casing having an opening at one end, an endless carrier in said casing for movement of said cosmetic supply toward and away from said opening, said carrier normally closing said casing opening and being provided with an aperture to register with said casing opening upon movement 10 of the cosmetic supply toward said opening to permit the projection therethrough of the cosmetic supply.

8. A combined closure means and cosmetic stick carrier for cosmetic stick containers comprising an endless loop, the carrier being characterized by the provision therein of an aperture for accommodation of a cosmetic stick.

9. A container for a cosmetic supply including a body member having openings at opposite ends 20 for the projection of said cosmetic supply, opposing side walls for said body member, a continuous shoulder on the inner face of each of said side walls and spaced from said body member to define therewith a guide-way, a channel in the inner face 25 of each of said side walls and extending in the direction of said opening, a cosmetic supply retaining member positioned in said channel, and a carrier member normally closing said openings connected to said cosmetic retaining member for 30 movement thereof toward and away from said

openings, said carrier member having portions positioned in said guide-ways and being provided with apertures to register with the casing openings to permit projection therethrough of the cosmetic supply.

10. A container for a cosmetic supply, including a casing having an opening at one end, a retainer means for the cosmetic supply movable in said casing, a flexible tape in said casing for moving the retainer means toward and away from 10 said opening, said tape normally closing said casing opening and being provided with an opening to register with said casing opening to permit the extension therethrough of the cosmetic supply and said tape being so associated with said retainer means as to simultaneously exert both a pushing and a pulling force thereon, and means 15 exterior of the casing for moving said tape.

11. A container for a cosmetic supply, including a casing having openings at opposite ends, an 20 endless carrier in said casing for movement of said cosmetic supply toward and away from said openings, said carrier normally closing said casing openings and being provided with openings to register with said casing openings to permit the 25 extension therethrough of the cosmetic supply, and means for selectively moving the endless carrier to extend the cosmetic supply through said casing openings.
